UNITED STATES PATENT OFFICE.

HARRY W. WILEY, OF BLACK LICK, PENNSYLVANIA.

CAN-OPENER.

1,311,028.

Specification of Letters Patent. Patented July 22, 1919.

Application filed April 11, 1917. Serial No. 161,262.

To all whom it may concern:

Be it known that I, HARRY W. WILEY, a citizen of the United States, residing at Black Lick, in the county of Indiana and State of Pennsylvania, have invented new and useful Improvements in Can-Openers, of which the following is a specification.

This invention relates to cutlery, and more especially to can openers; and its novelty and practical advantages will be clear from the following specification, reference being made to the drawings where-in:

Figure 1 is a plan view of this tool complete.

Fig. 2 is a longitudinal central sectional view on the line 2—2 of Fig. 1, showing the can opener at work on a can which is illustrated only in dotted lines.

Fig. 3 is a perspective view of the can opener mechanism removed from the arm of the tool proper.

Fig. 4 is a plan view of the blank from which this mechanism is made.

The main portion or frame of this device is made up of two arms 1 and 2 connected at one end by a nearly complete ring 3 which may be passed around the cover of a Mason jar so that, when the arms are brought together in the hand, a proper movement of the latter will unscrew the cover from the jar if it should happen to be stuck thereon. For this purpose the outer side of the ring may be made a little thinner or narrower as at 4, but otherwise the metal should be of considerable thickness as will be clear. One extremity of one arm, as 2, carries a hook 5 which will serve as a cap lifter. By inserting its tip under the cap and prying in the proper direction, the cap may be readily removed. The corresponding extremity of the other arm, as 1, carries a right angular "point" whose sharp end projects away from the ring 3 and on a line parallel with the normal position of the arms. This point 6 is for piercing the center of a can when its top is to be cut, as clearly understood. Only the end 7 of the point appears in Fig. 1, and it may be secured in the arm 1 in any suitable manner.

The hook or cap lifter, 5, however, appears in plan view in Fig. 1 from which it will be gathered that it stands in a plane at right angles to that of the point.

Slidably mounted on the arm carrying the point which arm is of rectangular form

in cross-section is the can-opening mechanism proper. The blank for this mechanism is best seen in Fig. 4, and in its folded condition it is best seen in perspective in Fig. 3. It may be made of sheet metal of proper stiffness, and should be treated to prevent rust. Its body is designated by the numeral 10. One end of the same is upward and provided with an opening 11 slidably mounted on the arm 1; in its body are cut slits producing the knife 12 and the guard finger 13, both of which are subsequently bent down as best seen in Fig. 2. Its other end carries two outstanding wings 14 which, in the final shape of this element, are bent upward around and slidably inclose the edges of the arm 1, and have their upper ends brought close together. Between these ends is pivoted a cam 15 on a pin or rivet 16, the lower end of the cam being slightly eccentric as shown in Fig. 2; and the cam preferably constitutes the handle for a cork screw whose spiral end 17 projects upward when the cam is turned to a position to bite onto the upper face of the arm 1. When the cam is folded down so that the cork screw lies along this arm, it no longer engages the latter and the entire device may be slipped longitudinally along the arm so as to set the knife 12 at proper distance from the point 6.

It will be observed that my improved specific construction is economical for the reason that the wings 14 at one end of the body 10 serve to hold the said body to the bar or arm 1, and also serve as standards for the cam member 15.

In the use of devices of this kind for opening cans, the point is first inserted through the center of the top and then swung down until the shank of the point or pin passes through the can-top, after which the knife 12 is jammed through the top near its edge, and the guard 13 passes over the side of the can. The entire device is swung around the point in the center, and the knife cuts the can on a substantially circular line. This is continued until the circle is almost complete, when the part cut therefrom is bent upward on what remains, serving as a hinge. While this broad principle is old in can-openers, the particular means for adjusting the cutting mechanism along the arm is, I believe, novel with me; and especially so when the cam 15 is used as the handle of a cork screw. The latter has to

be turned outward at right angles to the arm 1 to be used, and when it is turned down alongside the same, the element 10 can be adjusted in a manner above described.

Thus there is produced a combination tool including all the features necessary for opening a container. If the latter be a can, its top is cut; if it be a bottle, its cork is drawn; and if it be a Mason jar or the like, its cover can be unscrewed or its cap lifted.

What is claimed as new is:—

The herein described can opener consisting essentially of a bar of rectangular form in cross-section, a penetrating point secured at one side of the bar and projecting outwardly parallel to the bar and beyond the end thereof, a carriage slidable upon said bar; said carriage including a plate of sheet-metal disposed against the flat under

side of the bar and having a cutter and a guide struck therefrom and bent at right angles thereto, and arranged in spaced relation, an outer end portion bent in an opposite direction at right angles to the plate 25 and apertured for the passage of the bar and upwardly bent portions formed at the inner end of the plate and snugly fitting the flat sides of the bar and merging into inwardly extending portions disposed above 30 the upper side of the bar and provided at their inner ends with spaced apertured ears, whereby said portions are adapted to hold the inner end of the carriage to the bar, and a cam member mounted between said ears 35 for adjustably fixing the carriage on the bar.

In testimony whereof I affix my signature.

HARRY W. WILEY.
